UNITED STATES PATENT OFFICE

2,450,194

ADJUSTABLE RETRCTOR

Mark Albert Glaser, Los Angeles, Calif.

Application July 22, 1946, Serial No. 685,516

2 Claims. (Cl. 128—20)

1

This invention relates to surgical instruments and particularly pertains to an adjustable retractor.

In performing various surgical operations it is necessary to provide mechanical means for holding tissue and muscular parts of the body in separated relation to each other. In view of the fact that this can only be accomplished by pulling and stretching the muscles and tissue, it is difficult to perform such operations by the direct application of manual force, and it is furthermore difficult to hold the body muscles and tissue in a retracted position so that an operation may be deftly performed. Heretofore retractors have been provided which have been designed along the lines of a pair of forceps. These structures have included blades formed with a series of prongs to engage the body tissue and muscle and to retract the same when leverage is applied to the handles of the forceps. Such structures are often equipped with latch means for holding the blades in their retracting position. In view, however, of the fact that the arms of the forceps carrying the blades swing on an arc the setting of the blades may be disturbed to cut or mutilate the tissue or muscle objectionably. It should also be pointed out that in such structures the amount of leverage applied is limited by the length of the lever arms of the forceps.

Another type of forceps has been provided in which parallel arms are mounted upon a transverse frame structure and carry retractor blades at their outer ends. These parallel arms are spread by the application of manual force without leverage after which the arms are fastened in position by set screws. This particular form of structure has advantages in that it does not obstruct the operating area although it is difficult to apply the necessary retracting force.

It is the object of the present invention, therefore, to provide a retractor for use in surgical operations in which a pair of parallel side arms carry retractor blades and which arms are mounted on a cross-element and are associated with leverage means designed to apply great force in separating the retractor arms and being fitted with locking means.

The present invention contemplates the provision of a surgical retractor having a retractor arm and a rack arm formed integral, said rack arm receiving a slidable cross-head carrying a retractor arm parallel to the first named retractor arm, the cross-head and retractor arm being fitted with ratchet means whereby the retractor

2

arms may be separated by the application of great force, the structure further including means for locking the arms in a set position, and a pair of removably pronged blades, one adjustably mounted on each of said retractor arms.

The invention is illustrated by way of the accompanying drawings in which:

Figure 1 is a view in side elevation showing the retractor with its arms partially separated.

Fig. 2 is a view in end elevation showing the structure of Fig. 1.

Referring more particularly to the drawings, 10 indicates a rack bar here shown as formed along one edge with a series of rack teeth 11. The bar is preferably rectangular in construction with the teeth being cut transversely of its narrow width. Formed integral with the rack bar is a relatively fixed retractor arm 12 which is disposed at right angles to the bar 10. This bar is also preferably rectangular in cross-section although it will be understood that the invention is not so limited. Adjacent to the juncture of bars 10 and 12 is a handle 13 which extends in a plane substantially parallel to the plane of the bar 12. Mounted upon the bar 12 is a blade structure 14 which as shown in Fig. 2 of the drawings is formed with a tubular sleeve of rectangular cross-section as indicated at 15, and through which a rectangular opening 16 is formed to accommodate the rectangular section of the bar 12. Formed integral with the sleeve 15 are a series of retractor prongs 17. These prongs are preferably disposed in a plane parallel to one side face of the sleeve and terminate in inturned teeth 18, the inner faces of which are parallel to the opposing face of the sleeve 15. A set screw 19 is threaded through the wall of the sleeve 15 to engage the outer edge face of the retractor bar 12 and by which the unit 14 is locked in a desired adjusted position on the bar 12.

A cross-head 20 is mounted to slide upon the rack bar 10. This cross-head is formed with a central rectangular opening through which the bar 10 extends. Formed integral with the outer face of the cross-head is a handle 21 which is in a plane parallel to the handle 13. Formed integral with the cross-head 20 and extending diametrically opposite from the handle 21 is a movable retractor bar 22. This bar is of rectangular cross-section and size the same as bar 12, and receives a retractor unit 23 at its outer end. This unit is formed with a tubular sleeve 24 having a central rectangular opening 25 through it to accommodate the retractor bar 22. A plurality of retractor prongs 26 are formed along

one edge of the sleeve 24 and are here shown as being disposed in a direction toward the retractor bar 12. These prongs terminate in teeth 27. Retractor unit 23 is held adjustably on the bar 22 by a set screw 28. It will be evident that the retractor units 14 and 23 may be set at any desired position along the length of the bars 12 and 22 and that it is desirable to space the prongs of the two retractor units in a manner to insure that the ends thereof may extend into the intervening space between the complementary prongs. This makes it possible to place the portions 18 and 27 of the prongs close together when the retracting operation is initiated. It will be obvious that the bars 12 and 22 might be pulled apart by manual force applied to them or to the handles 13 and 21. This requires the application of violent force which is objectionable and also inconvenient. In order to separate the retractor bars 12 and 22 easily and with great force a ratchet pawl 29 is provided with a toothed end 30 which will engage or ride over the teeth 11 on the rack bar 10. This pawl is mounted upon a link 31 by a pivot pin 32. The link 31 is mounted upon a pivot pin 33. This pin is carried by ears 34 extending from the edge of the lock bar 22. A spring 35 connects the free end of the shackle 31 to the cross-head 20 and tends to dispose the shackle 31 parallel to the movable retractor bar 32, and to draw the teeth 30 of the pawl 29 toward the cross-head 20. Pivotaly mounted upon the pivot pin 32 is a lever arm 36 formed with a handle 37 at its outer end. This provides a means whereby force may be applied to move the pawl 29 toward the cross-head 20.

Mounted upon the cross-head is a latch lever 38 which is pivoted at 39. The lever extends substantially parallel to the handle 21 and is urged away therefrom by a spring 40. The inner end of the latch lever is fitted with a lock-dog 41 which will impinge against the edge of the rack bar 10 and will tend to lock the cross-head 20 and the rack bar 10 against relative movement.

In operation of the present invention the structure is made and assembled as shown in the drawings after which it is ready for use. When the surgeon has made an incision he may then select retractor elements 14 and 23 which will be appropriate for the operation. These may be adjusted lengthwise of the retractor bars 12 and 22 and temporarily fixed by the set screws 19 and 28. A lever 38 may be pressed toward the handle 21 in the direction of the arrow *a* as shown in Figure 1 so that the dog 41 will be released from locking engagement with the rack bar 10. The lever arm 37 may then be moved in the direction of the arrow *b* as shown in Figure 1. This will cause the pawl 29 to swing in the direction of the arrow *c* and clear the teeth 11. The retractor bars 12 and 22 may then be moved toward each other so that their prongs will be properly positioned within the incision. The rack bars 12 and 22 may then be separated manually at which time the pawl 29 will ride over the teeth 11. Additional force may then be applied by swinging the operating lever 36 in a direction opposite that indicated by the arrow *b*. This will cause the pointed end 30 of the pawl 29 to engage the rack teeth and will force the rack bar 10 in the direction of the arrow *d* as shown in Figure 1. This will separate retractor units 14 and 23. When these units are separated a desired distance the lever 38 may be released so that the lock dog 41 will be forced against the edge of the rack bar 10 by the spring

40 and will hold the retractor arms in a fixed position. When it is desired to remove the retractor the dog 41 may be released as well as the pawl 29 so that the retractor arms 12 and 22 may move toward each other freely. In order to sterilize the instrument it is obvious that the units 14 and 23 may be quickly removed by manipulation of the screws 19 and 28 and that the retractor bar 22 with its cross-head and associated mechanism may be easily separated from the rack bar.

It will thus be seen that the structure here disclosed provides a retractor of simple construction whereby a direct application of force may be applied from a remote and convenient point so that an incision may be stretched open and may be held in such position while the surgical operation is performed, the structure making it possible for power of great magnitude to be applied by members which may be easily locked in their set position.

While I have shown the preferred form of my invention, it is to be understood that various changes may be made in the combination, construction and arrangement of parts, by those skilled in the art, without departing from the spirit of the invention as claimed.

Having thus described my invention, what I claim and desire to secure by Letters Patent is:

1. Surgical retractors comprising a rigid retractor bar, a rack bar integral therewith and disposed at right angles thereto, a movable retractor bar unit including a cross-head slidably mounted upon the rack bar, a retractor bar integral therewith and extending parallel to the first named retractor bar, handles on the first named retractor bar structure, a cross-head whereby the retractor bars may be moved directly toward and away from each other, rack teeth along one edge of the rack bar, a pawl adapted to engage said rack teeth, and a lever mechanism associated with said pawl and carried by the movable retractor bar structure whereby the two rack bars may be moved apart forcibly.

2. Surgical retractors comprising a rigid retractor bar, a rack bar integral therewith and disposed at right angles thereto, a movable retractor bar unit including a cross-head slidably mounted upon the rack bar, a retractor bar integral therewith and extending parallel to the first named retractor bar, handles on the first named retractor bar structure, a cross-head whereby the retractor bars may be moved directly toward and away from each other, rack teeth along one edge of the rack bar, a pawl adapted to engage said rack teeth, a lever mechanism associated with said pawl and carried by the movable retractor bar structure whereby the two rack bars may be moved apart forcibly, a lock lever pivoted upon the cross-head and a lock element associated therewith whereby the edge of the rack bar may be engaged to hold the cross-head against movement relative to the rack bar.
